APPARATUS FOR ADJUSTING AND HOLDING WELL DRILLING BITS

Original Filed August 7, 1925 2 Sheets-Sheet 2

UNITED STATES PATENT OFFICE.

JAMES M. SHAFFER, OF FORT WORTH, TEXAS.

APPARATUS FOR ADJUSTING AND HOLDING WELL-DRILLING BITS.

Application filed August 7, 1925, Serial No. 48,726. Renewed September 13, 1926.

My invention relates to apparatus for handling well drilling bits and tools and the like; and the object is to provide certain simple devices for engaging and handling well drilling bits and other tools and to provide apparatus which will be strong and which will operate with required accuracy and positiveness and which is capable of quick adjustments and which will hold the tools from slipping. Other objects and advantages will be fully explained in the following description and the invention will be more particularly pointed out in the claims.

Reference is had to the accompanying drawings which form a part of this application.

Fig. 1 is a plan view of the tool holder, showing in dotted outline a drill bit.

Fig. 2 is a side elevation of the same, showing the manner of attaching the apparatus to a crane.

Fig. 3 is an edge view of the same.

Fig. 4 is an enlarged broken view, showing the bearing of one of the adjusting blocks, the nut and the swivel being omitted.

Fig. 5 is an enlarged sectional view of one of the tool holders.

Fig. 6 is a face view of the same, showing the corrugations for engaging the tools.

Fig. 7 is an enlarged sectional view of the bearing of the tool holder and the means for adjusting the tool.

Similar characters of reference are used to indicate the same parts throughout the several views.

This invention includes a quadrangular frame composed of bearing members 1 and 2 and adjusting members which are composed of co-operating members 3 and 4, 5 and 6. The members 3 and 4 and 5 and 6 have corrugated interlocked faces 7 for adjusting purposes. Bolts 8 and nuts 9 hold the member 3 and 4 and 5 and 6 interlocked. These members 3 and 4 and 5 and 6 have slots 10 for permitting adjustments without removing the bolts entirely. The nuts 9 are unscrewed sufficiently to permit the points of the corrugations 7 to pass each other.

The proper adjustment is made and then the nuts are tightened. To prevent outward movement of the bearing member 2, the member 4 is provided with upstanding lugs 11 and downwardly projecting lugs 12 on both sides of the member 2. The object is to prevent endwise movement of the bear-

ing member 2 after the tool is properly adjusted. For the same reason the member 3 is provided with upstanding lugs 13 and downwardly projecting lugs 14. The member 1 cannot be moved endwise of the apparatus after the adjustment is made and the nuts 9 are tightened.

The lugs 11 and 12 are placed on the member 4 and the lugs 13 and 14 are placed on the member 3 so that members 3 and 4 can be adjusted longitudinally relative to each other. The members 5 and 6 are not provided with such lugs because these members form the gate for inserting and removing tools from the apparatus. A bolt 15 and nut 16 are used at one corner to hold the member 6 in place the bolt 15 forming a hinge for swinging the members 5 and 6. An eye bolt 17 holds the member 5 and the member 1 in operative relation after the adjustment has been made. The ends of the members 1 and 2 are slotted so that members 3 and 4, and 5 and 6 can be adjusted laterally and the members 1 and 2 are provided with pluralities of holes 18 for the bolts 15 and 19 for adjusting purposes.

Bearings 20 are mounted in the members 1 and 2 for the adjusting blocks 21 and the bearings 20 may be cast integral with the members 1 and 2. The bearing members 20 have reduced portions to form supports or engaging members 25 for the swivel connections 22. The tool or apparatus is suspended on a crane by a block 23 and chains 24 which engage the swivels 22.

The faces of the adjusting blocks 21 are provided with corrugations 26 to prevent the tools from slipping through the apparatus or gripping members. The faces may be simply serrated in any suitable manner to make secure the holdings of drill bits and other tools. The blocks 21 are adjusted through their bearing connections by means of eye or other bolts 27, which are threaded and operate through threaded portions of the bearings 20. The movement of the bearing or adjusting blocks 21 may be limited by set screws 28 which project into the annular grooves 29 in the adjusting blocks 21, these grooves being sufficiently wide to permit adjustments without moving the screws.

For inserting a tool or bit, the bolt 17 may be removed and the members 5 and 6 swung outwardly on the bolt 15. After the tool is brought within the frame, the mem-

bers 5 and 6 will be swung back into place and the bolt 17 inserted. The swivel connections 22 are necessary because the tools must be turned to horizontal position to be 5 dressed.

What I claim is,—

1. A tool holder for well operating tools comprising a horizontal frame having end bearing members, one fixed side member connecting said end members in operative relation, one movable side member operatively connected to said end members and forming a gate for inserting and removing tools from said frame, and adjustable blocks mounted 10 in said bearing members, for carrying the tools.
2. A tool holder for well operating tools comprising a horizontal frame having end bearing members and side members operatively connected to said end members, each side member being composed of two members having their adjacent faces corrugated and capable of meshing with each other at different longitudinal adjustments, and tool holding members carried by said end members. 20
3. A tool holder for well operating tools comprising a horizontal frame having end bearing members and one fixed side member and one movable side member, said movable side member forming a gate for the frame, and said fixed member having upwardly and downwardly projecting lugs for holding said end members at fixed adjustments, and tool holding members carried by said frame. 30
4. A tool holder for well operating tools comprising a horizontal frame having end bearing members and side members operatively connected to said end members, one side member being fixed and the other side member being movable and forming a gate, 40

each side member being composed of two members corrugated on their adjacent faces and capable of longitudinal adjustment relative to each for adjusting said frame, said 45 side members having elongated slots and bolts projected through said slots and through said members and provided with nuts for holding said corrugated members in mesh at different points of adjustment, lugs 50 on said side members for preventing movement of said end members after the end members have been adjusted, and tool holding members carried by said end members.

5. A tool holder for well operating tools 55 comprising a horizontal frame having end members and side members adjustably connected thereto, said end members having bearings, adjustable blocks mounted in said bearings and constituting tool holding members, and bolts for adjusting said blocks. 60

6. A tool holder for well operating tools comprising a horizontal frame having end members and side members adjustably connected thereto, bearings carried by said end 65 members, tool holders mounted in said bearings, and screw bolts operatively connected with said bearings for adjusting said tool holders.

7. A tool holder for well operating tools 70 comprising a horizontal frame having end members and side members operatively connected thereto, said end members having bearings, tool gripping members mounted in said bearings, screw bolts operatively connected 75 with said bearings for adjusting said gripping members, and swivel connections operatively connected with said bearings for connecting said tool holder to a crane.

In testimony whereof, I set my hand, this 80
4th day of August, 1925.

JAMES M. SHAFFER.
